UNITED STATES PATENT OFFICE.

FREDERIK H. HUNGUS, OF NEW YORK, N. Y.

CABINET WASH-STAND.

SPECIFICATION forming part of Letters Patent No. 416,919, dated December 10, 1889.

Application filed January 12, 1889. Serial No. 295,920. (No model.)

To all whom it may concern:

Be it known that I, FREDERIK H. HUNGUS, a citizen of Germany, residing in the city, county, and State of New York, have invented 5 certain new and useful Improvements in Cabinet Wash-Stands, of which the following is a specification.

This invention relates to an improved cabinet wash-stand that can be entirely closed up 10 when not in use; and the invention consists of a cabinet wash-stand provided with side and rear walls, a recessed top plate, hinged front doors, and a hinged top lid, said doors and lid being provided with looking-glasses, so 15 that they can be used conveniently as mirrors when the wash-stand is in open position.

The invention consists, also, of the combination, with a bureau or other piece of furniture, of a wash-stand formed of side and rear 20 walls, hinged front doors, a recessed top, and a lid hinged to said top.

In the accompanying drawings, Figure 1 represents a perspective view of my improved cabinet wash-stand, shown in open position. 25 Fig. 2 is a front elevation of the same, shown in closed position; and Fig. 3 is a vertical transverse section on line $x-x$, Fig. 2.

Similar letters of reference indicate corresponding parts.

30 In the drawings the wash-stand is shown as arranged above a bureau A, having a suitable number of drawers. The side and rear walls of the bureau A are extended in an upward direction above the top of the bureau, so as 35 to inclose a space of sufficient size for a wash-stand. This space is closed by hinged front doors C C and a top lid D, which is hinged to a recessed top B. The front doors and top lid are provided with looking-glasses C' and D' at their inner surfaces, the looking-glass of the top lid being used when standing, while the looking-glasses of the front doors are used when sitting in front of the wash-stand. The looking-glass of the top lid D is hinged 45 at its upper edge to the under side of the top lid D, and retained thereon by a suitable clasp d, which engages the lower edge of the looking-glass, so as to permit it to be used when the top lid is in open position, as shown 50 in Fig. 1. When releasing the clasp d and closing the top lid, the looking-glass assumes a pendent position at the front part of the wash-

stand, as shown in dotted lines in Fig. 1, which is of special convenience for ladies, in connection with the looking-glasses of the front doors C, in dressing their hair. The top lid D rests on ledges b of the recessed top plate, and is retained in position by arc-shaped guide-strips e, which are attached to the lid D, guided in a recess e' of the ledges, and 60 clamped by set-screws e², as shown in Fig. 1.

When the doors C and lid D are opened, the wash-stand is accessible, it containing all the accessories of a wash-stand, such as a basin, pitcher, soap-dish, towel-rack, &c. 65 When the doors are closed, the wash-stand is out of sight, so that it can be located in any room without the objectionable appearance of a wash-stand.

Above the top of the wash-stand is arranged 70 an ornamental panel, which may also be provided with a looking-glass for additional ornamentation.

The wash-stand can be used in connection with a bureau, as shown in the drawings, or 75 in connection with a chiffonier or other piece of furniture, or separately, by being supported at a suitable height on a table or other support.

My wash-stand has the advantage that the 80 washing utensils are ready for use immediately on opening the wash-stand, without requiring to be moved into the wash-stand and removed from the same after use.

Having thus described my invention, I 85 claim as new and desire to secure by Letters Patent—

A cabinet wash-stand or other piece of furniture formed of side and rear walls, hinged front doors, a recessed top, a cover hinged to 90 said top, a mirror hinged at its upper edge to said cover, and a locking device that engages or releases the lower edge of said mirror, so as to retain it on the cover or permit it to hang in a pendent position therefrom, substantially as set forth.

In testimony that I claim the foregoing as my invention I have signed my name in presence of two subscribing witnesses.

FREDERIK H. HUNGUS.

Witnesses:

PAUL GOEPEL,
JOHN A. STRALEY.
